SHOCK ABSORBER FOR THE BALANCE
STAFF OF WATCHES

Gérard Erismann, Neuveville, Switzerland

Application October 7, 1940, Serial No. 360,181
In Switzerland October 30, 1939

5 Claims. (Cl. 58—140)

This invention relates to shock absorbers for the balance staff of watches.

These shock absorbers comprise a ring in which a jewel for the balance staff is set, which ring, in its turn, is arranged in the center of an elastic arrangement of greater diameter, said elastic arrangement being carried by a setting placed in a hollow of the flat part of the balance cock.

One object of my invention is to construct the elastic arrangement and the setting as a whole.

Another object is to provide a ring forming a whole with said setting and comprising a spiral spring and another ring in which said jewel is set and which forms the inner end of said spiral spring.

A further object is to make the setting in one piece with said ring or to force the latter into said setting.

Still another object is to provide a second setting placed on the first setting and made in one piece with a second elastic arrangement being supported on the cap-jewel. In a special embodiment this second elastic arrangement can be made in one piece with the cover plate.

Other objects and features will be apparent as the following description proceeds, reference being had to the accompanying drawing in which

Fig. 1 is a vertical section through the balance staff of an embodiment;

Fig. 2 is a top view with cover plate, index and cap-jewel removed;

Figs. 3 and 4 are vertical sections through the balance staff of other embodiments.

In the embodiment shown in Figs. 1 and 2, 1 represents the flat part of the balance-cock to which a cover plate 2 is screwed; the index 3 fitting, as usual, the circumference of this cover plate. An aperture is provided on the cover plate in which, by insertion of a collet 4 and flexible tongues 5 forming the object of a former invention, a cap-jewel 6 is held, serving the purpose of absorbing the axial component of the shocks to which the balance staff is exposed.

The arrangement according to the present invention is intended to absorb the radial component of these shocks. It comprises a setting 8, an elastic member consisting of a ring 9 and of a spiral spring 10 ending in a ring 11, and a perforated jewel 12. The setting 8 is inserted into a circular recess of the part 1 and is supported on the bottom of said recess. The perforated jewel 12 is set in the ring 11, which is in the center of the elastic member. In this

embodiment the two portions of the elastic member, viz.: the spiral spring 10 and the ring 9 are made in one piece with the setting 8. The ring 9 could, however, just as well be forced into the setting 8 or fixed to the setting in any other suitable way.

It is understood that the elastic member may be different from that above described and illustrated. It could, for instance, have any form of the arrangements shown in the Swiss Patents 186,317, 192,767, 192,768.

In Fig. 3 an example is illustrated, which is distinguished by the feature that the setting of the elastic member or arrangement carries a second setting. A second elastic member, being supported on the cap-jewel, is made in one piece with this second setting. In this Fig. 3, 1 again represents the flat part of the balance cock, into a recess of which the setting 8 made in one piece with the spiral spring 10, is inserted. The center of this spiral spring is formed as a ring into which a perforated jewel 12 is set, which, in its turn, serves as a bearing for the balance staff 7. A second setting 13 is fitted to the setting 8 with the help of a rim 14. The center part of this second setting 13 is formed by elastic lamellae constituting a spring, the cap-jewel being located under these lamellae. The number of these lamellae 15, disposed along radii of the setting, varies from three to six. These lamellae absorb the axial shocks to which the cap-jewel is exposed. Together with the setting carrying them, they constitute a second elastic member or arrangement completing the one formed by the spiral spring 10 and the perforated jewel 12. The fitting of the setting 13 to the setting 8 being rather close, the two devices form a handy whole which, as a single piece, can, accurately centered, be inserted into the corresponding recess of the part 1. The whole is kept in place by the cover plate 2. The cap-jewel 6, on its circumference, is so thick that it does not cant or fall out of the setting 13 whatever the shock, to which the timepiece in the direction of the shaft axis and away from the bearing is subjected, may be.

In the embodiment illustrated in Fig. 4 the same parts are seen as in the preceding one. The first elastic member or arrangement absorbing the radial shocks is, also in this embodiment, formed by the spiral spring 10 made in one piece with the setting 8. The second elastic arrangement is formed by the lamellae 21 made, in this case, in one piece with the cover plate 20 forced into the setting 8 of the first elastic

arrangement by means of a small rim. Thus, the two elastic arrangements form, together with the cover plate, a handy whole adapted to be easily removed and re-inserted. This whole is fixed by means of screws 16 going, with a little play, through the part 1. In this way the cover plate is accurately centered by means of the circumference of the first elastic member or arrangement. The cap-jewel, on its circumference, is so thick that it does not cant or fall out of the cover plate 20 whatever the shock, to which the time-piece in the direction of the shaft axis and away from the bearing is subjected, may be.

What I claim is:

1. In a watch, a balance staff, a jewel adapted to hold said balance staff pivotally, a balance cock comprising a flat part, a hollow on said flat part, a setting lodged in said hollow, an elastic arrangement forming a whole with said setting, a ring disposed in the center of said elastic arrangement forming a whole with said jewel, a cap-jewel, a second setting placed on said setting, a second elastic arrangement made in one piece with said second setting and adapted to press against said cap jewel.

2. In a watch, a balance staff, a jewel adapted to hold said balance staff pivotally, a balance cock comprising a flat part, a hollow in said flat part, a setting lodged in said hollow, an elastic arrangement forming a whole with said setting, a ring disposed in the center of said elastic arrangement and adapted to receive said jewel, a cap-jewel, a second setting fitted into said setting, a second elastic arrangement made in one piece with said second setting and adapted to press against said cap jewel.

3. In a watch, a balance staff, a jewel adapted

10 to hold said balance staff pivotally, a balance cock comprising a flat part, a hollow on said flat part, a setting lodged in said hollow, an elastic arrangement forming a whole with said setting, a ring disposed in the center of said elastic arrangement and adapted to receive said jewel, a cap-jewel, a cover plate fitting said setting, a second elastic arrangement made in one piece with said cover plate and adapted to press against said cap jewel.

4. In a watch, a balance staff, a jewel adapted to hold said balance staff pivotally, a balance cock comprising a flat part, a hollow in said flat part, a setting lodged in said hollow, an elastic arrangement forming a whole with said setting, a ring disposed in the center of said elastic arrangement and adapted to receive said jewel, a cap-jewel, a cover plate fitting said setting, a second elastic arrangement made in one piece with said cover plate and adapted to press against said cap-jewel, said cover plate and said setting being connected with one another in such a way as to form a whole centered in said hollow by means of the circumference of said setting.

5. In a watch, a balance staff, a jewel adapted to hold said balance staff pivotally, a balance cock comprising a flat part, a hollow on said flat part, an elastic member, a setting surrounding said elastic member and integral with and of greater thickness than said elastic member and extending beyond both front faces of said elastic member and lodged in said hollow, and a ring disposed in the center of and integral with said elastic member and adapted to receive said jewel.

GÉRARD ERISMANN.
